(57) **CLAIM**

The ornamental design for a non-planar, closed wing fin with stabilizer, as shown and described.

DESCRIPTION

FIG. 1 is a top perspective view of a non-planar, closed wing fin with stabilizer showing my new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a right side elevation view thereof;

FIG. 8 is a left side elevation view thereof;

FIG. 9 is a top perspective view of an alternate embodiment of a non-planar, closed wing fin with stabilizer showing my new design;

FIG. 10 is a bottom perspective view thereof;

FIG. 11 is a top plan view thereof;

FIG. 12 is a bottom plan view thereof;

FIG. 13 is a front elevation view thereof;

FIG. 14 is a back elevation view thereof;

FIG. 15 is a right side elevation view thereof; and,

FIG. 16 is a left side elevation view thereof.

The broken lines illustrate portions of the non-planar, closed wing fin with stabilizer that form no part of the claimed design.
